(57) **CLAIM**

(**) Term: **14 Years**

(21) Appl. No.: **29/151,137**

The ornamental design for a user interface design for a television display screen, as shown and described.

(22) Filed: **Nov. 1, 2001**

DESCRIPTION

(51) LOC (7) Cl. **14-02**

The single FIGURE is a front view of a user interface on a television display screen showing our new design.

(52) U.S. Cl. **D14/486**

The broken line drawing of a television display screen is for illustrative purposes only and forms no part of the claimed design.
